UNITED STATES PATENT OFFICE

136,571

DESIGN FOR A CIGARETTE CONTAINER

Nicholas Testi, Boston, Mass., assignor to Gillette Safety Razor Company, Boston, Mass., a corporation of Delaware

Application January 29, 1943, Serial No. 109,361

Term of patent 3½ years

To all whom it may concern:

Be it known that I, Nicholas Testi, a subject of the King of Italy, residing at the city of Boston, in the county of Suffolk and Commonwealth of Massachusetts, have invented a new, original, and ornamental Design for a Cigarette Container, of which the following is a specification, reference being had to the accompanying drawing, forming part thereof.

The figure is a perspective view of a cigarette container, showing my new design. The rear of the cigarette container is substantially the same as its front and the far side is the same as the side shown.

I claim:

The ornamental design for a cigarette container, as shown and described.

NICHOLAS TESTI.
